WELL FLUID SAMPLER

George A. Macready, Los Angeles, Calif.

Application September 14, 1936, Serial No. 100,663

10 Claims. (Cl. 166—1)

My invention relates to bore holes or drilled wells in which it is desired to test formations penetrated by the drill to determine the character of fluid in such formations.

5 My invention is an improvement over the inventions disclosed in my United States Patents Numbers 1,896,492, 1,896,522, 1,921,472 and 2,040,619.

An object of my invention is to provide a tubular apparatus having a packer or sealing means adjacent its lower end and which can be lowered into a well to seal off fluid above the seal from entering the tube. The apparatus has weight operated valves which be opened to admit a sample 15 of fluid from formations below the level of seal and then closed after admission of the sample to the tube to exclude additional fluid from entering the tube after breaking the seal, weights for operating the valves, means for suspending the 20 weights and dropping them at the desired time, a swivel so that the tube can be rotated while the sample is entering, a detachable bulky member below the seal to displace as much as possible of the fluid from the well below the seal which would 25 otherwise dilute the sample, and an emergency circulation outlet.

An object of my invention is to provide a valve for a well fluid sampler that can be lowered locked in open position and then unlocked by dropping 30 a weight on it to permit it to close.

An object of my invention is to provide a novel emergency circulation port for a well fluid sampler.

An object of my invention is to provide a bulky 35 detachable mud displacer member below the packer of a well fluid sampler that will displace as much of the drilling fluid below the seal as is possible in order to lessen dilution of the sample by drilling fluid and which is made of non-metallic 40 material that can be destroyed by the drill in the event it becomes stuck in the well when the sampling apparatus is pulled out.

An object of my invention is to provide a novel efficient swivel for a well fluid sampler.

45 An object of my invention is to provide an efficient and novel means for suspending weights ready to be dropped when desired through the sampling tube to operate the valves of a well fluid sampler.

50 With the foregoing and other objects in view which will be made manifest in the following detailed description and especially pointed out in the appended claims, reference is directed to the accompanying drawings, in which similar numerals refer to similar parts throughout the

several views, for illustrative embodiment of my invention, wherein:

Figure 1 is an elevation of the upper and lower portions of my apparatus in suspended position,

5 Figure 2 is a longitudinal section of the upper end of my apparatus showing the means for suspending and releasing weights,

Figure 3 is a longitudinal section of the ball and seat valve for preventing escape of the fluid sample,

10 Figure 4 is a longitudinal section of the flap valve which is held open until the sample is received and then closed,

Figure 5 is a longitudinal section of the lower portion of my sample tube showing the valve 15 which excludes fluid from the tube until ready for the sample, the packer, the swivel and the emergency circulation port,

20 Figure 6 is a longitudinal section of the mud displacer member below my sample tube showing the longitudinal passages on its external surface, the releasable swivel connection to the sample tube and perforations admitting sample to tube,

25 Figure 7 is a cross section at line 7—7' of Figure 6,

Figure 8 is a longitudinal section of a metal liner which may be used instead of the mud displacer member,

30 Figure 9 is a longitudinal section of a perforated bull plug or nipple which may be used instead of the mud displacer member,

35 Figure 10 is a longitudinal section of an optional construction of the means for suspending and releasing weights adapted to be inserted in the conventional drill column between the grief stem and main drilling swivel,

Figure 11 is an elevation of tubular member 65, and

40 Figure 12 is a cross section at line 12—12' of Figure 10.

45 Referring to the drawings my invention consists of the following major elements shown assembled in elevation in Figure 1 and in longitudinal section details in Figures 2 to 6: the sample tube A: the upper element B for suspending and dropping weights: the third or ball valve C for retaining sample against escape from sample tube A: the second or flap valve D which closes the sample tube A against entry of additional fluid after the sample has been taken: 50 the first or toggle valve E which closes sample tube A against entry of fluid until ready to admit sample: the swivel and emergency circulation ports and valves F to insure against the sticking of the sample tube A in the well: the 55

packer or sealing means G: and the tail element H occupying the well hole below the packer.

Described more in detail commencing at the lower end the lowest element is the tail element H. This is illustrated in Figures 1, 6 and 7 as a central solid mud displacer member 1 of sufficient diameter to almost completely occupy the well hole below the packer and provided with longitudinal grooves 2 on the external surface thereof. The mud displacer member may be solid with grooves cut in or it may be built up in sections as by wooden slats 3 attached by nails 4 to the central body 5 and spaced apart so as to leave the longitudinal grooves 2. In

10 the event the length of mud displacer member is long it may be made in units to be joined as by screw threads 6 or by selecting random length slats 3 so that the slats overlap the sections of body 5. The ribs 3 of each section may 15 be made short enough so that when sections of the mud displacer member are assembled a gap 7 is left between the ends of ribs 3 forming passages from each longitudinal groove to the adjacent groove through which in the event of 20 obstruction of any groove by debris the flow of fluid may be diverted to an adjacent groove to 25 continue its upward travel.

The mud displacer member 1 may be made 30 of wood or moulded from plastic material such as cement, fiber, stucco, plaster of Paris, etc., with the longitudinal grooves and end connections cut or moulded.

During a test fluid entering the well hole from 35 the formation passes upwardly along the annular space 124 between the mud displacer member and the well wall. In the event that the well wall caves the cavings bridge across over the longitudinal grooves whose purpose is to provide a channel for upward flow of fluid inside 40 the ring of cavings.

The lower end of mud displacer member 1 may be rounded or it may be irregular to resist 45 turning during its ensuing destruction by drilling. The upper end of mud displacer member 1 is attached to perforated tube 8 preferably by a rotatable swivel connection that can easily be sheared off by pulling in the event the mud displacer member sticks in the well as illustrated by readily destructible thimble 9 threaded into 50 the mud displacer member 1 above retaining boss 10. By making thimble 9 or an adjacent part of weak material it can be sheared off. By making mud displacer member 1 of nonmetallic material it can easily be destroyed by drilling.

The dimensions of mud displacer member 1 should be chosen so that it is bulky enough to 55 occupy most of the well below the packer G in order to displace as much as possible of the well drilling mud fluid from the lower part of the well hole, which fluid would otherwise dilute 60 the sample.

For example, in testing a formation having 400 pounds rock pressure in a rathole 200 feet long by 100 square inches cross section with a sample tube of 25 square inches internal cross section the volume of well drilling mud fluid in the rathole is equal to 800 feet of sample tube. By the time the mud fluid is displaced into the sample tube by the formation sample to rise 800 feet there is not sufficient pressure differential left 65 to force any formation sample into the sample tube. By displacing the fluid in the rathole with my mud displacer member of say 80 square inches cross section the volume of mud fluid remaining 70 in the rathole is only sufficient to cause a rise of 75

160 feet in the sample tube so that 640 feet of fluid from the formation can follow into the sample tube to cause a rise of 800 feet at the time the rock pressure is balanced with 400 pounds pressure. The result is a sample for inspection containing 80% of formation fluid when the mud displacer member is used in contrast to a sample containing practically no formation fluid when the mud displacer member is not used.

Because of the danger of a bulky object such as my mud displacer member becoming stuck in the well provision is made to detach same from the sample tube and to make it of material that can be destroyed by drilling so that the well may not be obstructed.

For the benefit of operators who prefer to fish out a liner the liner illustrated in Figure 8 may be used instead of my mud displacer member 1. This consists of a perforated liner having sections 11, 12 and perforations 16a which 20 may be joined by collars having left hand threads 13 above righthand threads 14. This is rotatably attached to a perforated tube 8a by means of a thimble 9a riveted to collar 15 above boss 10a. If the liner becomes stuck in the well 25 the rivets shear when the sample tube is pulled and the liner can be recovered by washing over it instead of destroying it by drilling. By using collars with lefthand threads a long liner may 30 be fished out piecemeal.

Another optional construction is shown by Figure 9 for use where neither liner nor mud displacer member are desired. It consists of the perforated bull plug or nipple 8b having no provision for attachment of mud displacer member 35 or liner and is useful for short ratholes.

Perforated tube 8 (8a or 8b) is provided with perforations 16 (16a or 16B) for admitting the sample of formation fluid into the interior thereof and is attached by coupling 18 to hollow spindle 19 which in turn is attached as by screw threads to valve case 20 which is the lowest member of the sample tube A. Threads 123 provide for attachment of instruments such as a bottom hole pressure bomb, inclinometer or thermometer.

Slidably and rotatably mounted about spindle 19 is a packer or sealing means G. A cone packer is illustrated for sealing against the shoulder 27 on the well wall at the top of a rathole 50 118 but where the well wall is vertical a straight wall packer may be used. The packer illustrated consists of a main tubular mandrel 150 rigidly attached to an upper end piece 21. A packing medium made up of discs 22 of rubber, belting 55 or other material mounted about mandrel 150 is held in compressed assembly between plates 23 and 24 by tightening screw collar 25. The external surface is turned to a taper to fit rathole shoulder 27. Guide knobs 26 preferably of bronze 60 on the lower end of mandrel 150 serve as bearings to align the mandrel on spindle 19. Springs 65 30 urge pins 28 outwardly to engage holes 33 in cap ring 29 to resist rotation of packing gland 31 on its recessed seat 32 but permit the pins to retract when they are not in alignment with holes 33.

Swivel F consists of an upper race 34 slidably keyed by key 151 on spindle 19 and a lower race 35 rotatably mounted about spindle 19 between 70 which rollers 36, either spherical or cylindrical, roll to reduce friction.

A projecting shoulder, preferably made by a split ring 37 in an annular recess holds the swivel in longitudinal assembly. Packing 38 is com- 75

pressed between gland 31 and ring 39 to prevent leakage of fluid past the swivel. Cap ring 29 holds the packing and gland in assembly.

The emergency circulation port consists of the outwardly opening check valve 40 in valve case 20 discharging through longitudinal holes 41, annular passage 42 of upper race 34, and longitudinal holes 43 of upper race 34 and thence out into the well between rollers 36. The check valve 40 normally remains closed to prevent fluid from without entering the sample tube but permits fluid circulation to be established outwardly in an emergency.

The first or toggle valve E is similar in construction to the toggle valve disclosed in my Patent Number 2,040,619. It is contained in valve case 20 and includes the ball valve 44 seating on seat 45 which is preferably of a renewable type controlling inlet passage 46 of member 47 attached in liquid tight fit to passage 48 through hollow spindle 19. A choke or bean 49 limits flow through passage 46 and may be selected of any desirable bore. Ball valve 44 is attached by bracket 50 to plate 51 and is held tight on its seat when pressure is applied by screwing down clamp ring 52 with toggle link 53 set. When a weight such as weight 54a dropped from its original position 54d shown in dotted lines on Figure 5 and strikes target arm 55 the toggle link 53 is moved over dead center to collapse the toggle and plate 51 can raise to lift valve 44 off its seat. Plate 51, toggle link 53, target arm 55 and their respective pivots are held in assembly by a frame consisting of side plates 56 attached to spacer 57 by screws 58.

A coupling 59 connects valve case 20 to valve case 60 which houses the second or flap valve D.

To facilitate removal for inspection and repairs the flap valve closure 61 is mounted on frame 64 on a liner 62 which in turn is attached internally in liquid tight fit in valve case 60. The valve 61 makes its closure by seating on lip 63 of liner 62 to close the central passage therethrough. When tubular member 65 is depressed against coil compression spring 66 the barbs 67 expand under shoulder 68 by cantilever springs 69 acting on the opposite end of the barb to pivot it about retaining ring or pin 70 fitted into an annular recess or hole in member 65 and in a notch 127 in each barb. The barbs are contained in slots 128 in tubular member 65. When tubular member 65 is depressed as shown in Figure 4 the flap valve 61 is held or locked in open position by the tubular extension 125 of tubular member 65. The bore of tubular member 65 is large enough to permit weight 54a to pass through pushing valve 61 wide open as it passes.

When it is desired to close valve 61 a second weight 71a is dropped from its original position 71d through sample tube A past position 71c shown in dotted lines on Figure 4. Weight 71a is provided with a wide dart or paddle 75 at its lower end wide enough to engage tubular plunger 72 to depress same against coil spring 73 and spread the lower ends of barbs 67 to retract the upper ends of barbs 67. With barbs 67 retracted the strong spring 66 expands to lift tubular member 65 upwardly out of engagement with valve 61 and cantilever spring 74 pushes flap valve 61 onto its seat 63 to close the passage into sample tube A.

The lower end of tubular member 65 is beveled as at 76 and screw 77 operating in longitudinal slot 78 insures proper alignment of the

bevel. Screw 79 holds plunger 72 in assembly. Wrench notches 80 provide for tightening liner 62 in position. A guide plate 82 is provided with a passage 81 to center weight 71a over plunger 72 and of sufficient bore to permit passage of both weights 54a and 71a. Rubber washer 83 completes assembly when tool joint pin 84 on the lower end of sample tube A is tightened.

The third or ball check valve C may be installed in any standard drill pipe tool joint preferably the lowest above the flap valve D. This valve consists of a ball 85 which is dropped through sample tube A, after dropping weights 54a and 71a, to seat on a disc 86 held by rubber washer 87 in low pressure liquid tight fit between box 89 and pin 90 of a tool joint as illustrated in Figure 3. The passage 88 through disc 86 should be large enough to permit passage of weights 54a and 71a but small enough to seat ball 85 to close sample tube A against escape of the formation fluid sample.

Sample tube A extends up to the top of the well and ordinarily is the drill pipe used in drilling the well.

The uppermost element B for releasably suspending weights is illustrated by Figure 2. Element B consists of a tool joint 92 attached by tool joint 91 to sample tube A and contains hollow spindle 93 rotatably mounted within so that the drill pipe may be rotated while the spindle and parts carried by it are not rotated. A stuffing box with packing 94 and gland 95 prevents fluid leakage. A cross 96 is attached by lefthand threads to spindle 93. Take off outlets 97 and 98 provide for discharge of sample fluid and may be controlled by valves or discharge to a line or hose. By anchoring with a rope to a leg of the derrick rotation of the cross and its fittings is prevented during rotation of sample tube A. A gate valve 99 may be provided above cross 96 if desired. A smaller gate valve or suitable clamp 100 is tightened about the second weight 71a as illustrated in Figure 2 to suspend the weight and a bull plug 101 prevents fluid leakage. A first weight as 54a is suspended by a cord 102 knotted through hole 103 in dart 75 of weight 71a passing thence through hole 104 in weight 54a and up along side of weight 71a to be passed outside through a smaller valve 105 and tied as at 106.

The first weight 54a is dropped by untying cord 102 at 106 and the second weight 71a is dropped by opening valve 100 to unclamp the weight.

An optional weight suspension means is illustrated in Figure 10. Left hand threaded tool joints 107 and 108 provide for attaching it between grief stem 122 and swivel 121 used in drilling the well. Pins 109 and 110 threaded through holes in hollow spindle 111 suspend weights 54b and 71b so that weight 54b may first be dropped to open toggle valve 44 and weight 71b dropped later to close flap valve 61. A take off casting 112 provided with packing 113, 114 to prevent leakage and with fluid outlets 115, 116 is mounted about spindle 111. Perforations 117 in spindle 111 provide for discharge of fluid from the sample through the outlets. A back pressure valve is shown at 120.

Operation

Drilling of a well hole proceeds until a formation is encountered which it is desired to test to determine the character of fluid that it may produce. The well bore is then enlarged by reaming to a level above the formation to be tested.

leaving a shoulder 27 preferably at a firm impervious stratum above a rathole 118 and below the large size hole 119. The well bore is usually full of the mud fluid used for drilling.

5 The assembly illustrated in the lower part of Figure 1 and in Figures 3 to 7 is then lowered into the well by means of a sample tube which usually is the rotary drill pipe used in drilling. During lowering valve 44 is locked closed, valve 10 61 is locked open and valve 85 is withheld at the surface.

Packer 22 is firmly seated on shoulder 27 by spudding if necessary. Cord 102 is cut or untied at 106 and released to permit weight 54a to fall 15 freely through the sample tube to pass through valve seats 86 and 76 to strike target 55 which kicks toggle link 53 over dead center and causes valve 44 to open. If the fluid level outside the sample tube subsides it indicates that the packer 20 has not made a proper seal and the apparatus should be withdrawn for a new trial.

If the fluid level in the well does not subside or the packer settle rotation of the sample tube is commenced. Packer G and the lower swivel race 25 35 remain stationary with spindle 19 rotating within. Fluid tight seals are made (1) by packer 22 against shoulder 27, (2) by gland 31 seating in recess 32, and (3) by packing 38 being compressed to seal about the rotating spindle 19 by 30 weight of sample tube applied through the packing to gland 31. The seal prevents fluid in the well above the seal from entering the sample tube or the formation being tested.

When my mud displacer member 1 is used below the packer most of the mud drilling fluid in the rat hole is displaced to above the packer leaving in the rat hole the small quantity between the mud displacer member and the wall of the well. Fluid from the formation tested 40 45 enters the rathole when pressure is relieved therein by opening valve 44 and displaces the mud fluid from the rathole up into the sample tube A following it up along the annular space between the mud displacer member and the well wall to also enter the sample tube to form the sample of formation fluid brought up for inspection. The sample passes through perforations 16 into tube 8 and through passages 46 and 48 through valve 45. During the admission of the 50 sample, the sample tube A can be rotated. Mud displacer member 1 may or may not rotate and may become stuck depending on the character of the well, because of its swivel connection at 10. Pins 33 lock the packer and lower swivel race 55 against rotation so as not to injure gland 31.

Rotation is continued until sufficient sample is believed taken or until difficulty of rotation warns of danger. Weight 71a is then dropped by opening valve 100. By closing valve 100 immediately it can be determined if the weight actually dropped. The weight falls through the sample tube and strikes tubular plunger 72 depressing it between bars 67 to contract them from under shoulder 68 and by momentum depresses spring 66 which rebounds to lift tubular extension 125 of tubular member 65 out of engagement with valve 61 and cantilever spring 74 then pushes the valve shut, preventing entrance of additional fluid to the sample tube. Hydraulic pressure on the lower side holds the valve closed.

The sample tube is raised after dropping weight 71a. After taking up the pipe stretch the internal flange of cap ring 29 engages under shoulder 126 on gland 31 to lift gland 31 off its seat 32 which permits fluid above the packer to

rush down between mandrel 20 and spindle 19 through the annular space to equalize the hydrostatic pressure on both sides of the packer.

Additional upward pull brings collar 18 against the bottom of packer mandrel 150 to jar the 5 packer upward. If the packer is stuck it may require lowering and raising the sample tube several times to jar the packer free from its seat. If mud displaces member 1 (or the liner) is stuck the thimble 9 (or 9a) being of weak material 10 strips or shears off leaving the core (or liner) in the rathole when the sample tube is raised.

When the packer has been pulled free the upper length of the sample tube with the upper connections is disconnected and ball 85 dropped through 15 the sample tube A to seat on its seat 86 and prevent the sample escaping from the sample tube when it gets above the fluid level of the well. The sample tube is then removed from the well a section at a time bringing up the sample of formation fluid contained within to the surface for inspection. The valves and packer are then removed from the well.

The drill is then lowered into the well and mud displacer member 1 being of soft material is 25 destroyed by drilling. Or the liner if left in the well can be fished out. The operation of drilling the well is then resumed.

In the event the sample tube itself should become stuck mud fluid or oil may be pumped down 30 through the sample tube and out through the emergency ports 40 to establish circulation to aid in loosening the tube.

The short perforated bull plug or nipple 8b may be used instead of either the mud displacer mem. 35 ber or liner particularly in short rat holes.

Instead of the construction shown in Figures 1 and 2 for the upper end of the sample tube the construction shown in Figure 10 may be used. Both have their advantages and disadvantages. 40 That in Figure 10 permits rotating the sample tube while suspended from the main drilling swivel but has the disadvantage that old grief stems still in use do not have a sufficiently straight passage to permit the weights to drop. 45

I claim as my invention:—

1. A well fluid sampler consisting of a sample tube, sealing means thereon adjacent the lower end of said tube for forming a seal between said tube and the wall of a well to exclude fluid in the 50 well above the seal from entering the interior of the tube, a roller bearing swivel between said tube and said sealing means providing for rotation of the tube while the well is sealed, emergency circulation ports consisting of outwardly opening 55 check valves with passages discharging between the rollers of the swivel, openings for admitting fluid from formation below the seal into the interior of said tube, a solid mud displacer member of non-metallic material having longitudinal channels on the external surface thereof releasably and rotatably attached to said tube below said seal and of sufficient volume to displace most of the drilling fluid from the well bore below the level of the seal, a first valve in said tube above said sealing means provided with a lock to close said pipe against entrance of fluid and adapted to be unlocked by dropping a first weight thereon to open said valve to admit a sample of fluid into said tube, a second valve positioned in said tube above 70 said first valve and provided with a lock holding it in open position and adapted to be unlocked by dropping a second weight thereon to permit said second valve to close and exclude entry of additional fluid into said tube, the bore of said second 75

- valve being great enough to permit passage of the first weight, a third valve adapted to be dropped into said pipe to seat on a constricted member in the tube above the first and second valves, clamps adjacent the upper end of said tube for suspending the first and second weights releasably so that each may be dropped by releasing the clamp, and outlets for discharge of a fluid sample from the upper end of said tube.
- 5 2. In a well fluid sampler, a sample tube, a valve in said tube, a tubular member in said tube adapted to hold said valve in open position, barbs on said member engaging a shoulder on the interior wall of said tube, a tubular plunger between 10 said barbs, a weight adapted to strike said plunger to depress the plunger and retract the barbs from said shoulder, and a spring urging said tubular member out of engagement with said valve when said barbs are retracted so that the valve may 15 close to prevent upward flow of fluid through said tube.
3. In a well fluid sampler having a sample tube and sealing means thereon adjacent the lower end thereof: a solid mud displacer member releasably and rotatably attached to said tube provided with longitudinal grooves for passage of fluid along the external surface thereof and of sufficient volume to displace most of the drilling fluid in a well below the level at which the sealing 20 means is set, said mud displacer member being constructed of nonmetallic material to permit its destruction by drilling when detached from said tube.
4. In a well fluid sampler having a sample tube and sealing means thereon adjacent the lower end thereof: a solid mud displacer member of nonmetallic material releasably and rotatably attached to said tube and provided with longitudinal 25 grooves along the external surface.
- 40 5. In a well fluid sampler having a sample tube and a valve adjacent the lower end of said tube operated by dropping a weight thereon: a clamp adjacent the upper end of said tube for releasably suspending said weight within said tube and 45 means on said clamp operable from outside said tube for releasing said weight to drop to said valve.
6. In a well fluid sampler having a sample tube and a packer thereon adjacent the lower end of said tube: a swivel providing for rotation of said tube relative to said packer and having a packing gland adapted to seat on said packer and support weight from said tube to compress a packing sealing against leakage between said tube and packer during rotation.
- 10 7. In a well fluid sampler having a sample tube, a packer adjacent the lower end thereof, and a roller bearing swivel between said tube and packer: an emergency circulation outlet having a check valve opening outwardly from the interior 15 of said tube and channels disposed to discharge fluid between the rollers of said swivel.
8. In a well fluid sampler: a valve housing having a central longitudinal passage therethrough, a valve seat in said passage, a valve adapted to seat on said seat to close said passage, and a lock 20 adapted to lock said valve in open position, said lock being unlocked by a blow from a weight to leave said valve free to close said passage against upward flow of fluid.
9. In a well fluid sampler having a sample tube with a sealing means thereon adjacent the lower end of said tube: a mud displacer member of nonmetallic material having a solid central portion and attached to said tube below the sealing means 25 so as to be inserted into a well cavity below the seal to displace a substantial quantity of the drilling mud from said cavity before admitting a sample to said tube, the external diameter of said mud displacer being nearly as great as the well 30 cavity.
10. In a well fluid sampler having a sample tube with sealing means thereon adjacent the lower end of said tube: a mud displacer member attached to the tube below said sealing means and 35 consisting of a solid central longitudinal body with longitudinal grooves along its external surface.

GEORGE A. MACREADY. 45
